UNITED STATES PATENT OFFICE.

CARL THILO MÜNZER, OF HAMBURG, GERMANY.

MULTIPLE-BARRELED GUN.

Application filed August 8, 1924. Serial No. 730,964.

To all whom it may concern:

Be it known that I, CARL THILO MÜNZER, citizen of Germany, residing at Hamburg, Germany, have invented certain new and useful Improvements in Multiple-Barreled Guns, of which the following is a specification.

The present invention relates to improvements in multiple-barreled guns, rifles and combination guns and rifles, and refers more particularly to the connection of the barrels with an undivided chamber-piece or breech and to the method of performing such connection.

Up to the present it was customary to connect the barrels with the chamber-piece or breech by hard soldering. But this mode of connection has the disadvantage, that the barrels are liable to become seriously affected by the great heat and to become distorted, and moreover must be subjected together with the chamber-piece to a final finish. This finish requires a disproportionate amount of time, as the chamber-piece and the barrels soldered thereto can only be worked and fashioned with great difficulty.

Although this disadvantage has been known for years no substitute method complying with the economical and technical requirements has up to the present been suggested. Some time ago a method of securing the barrels to the breech was proposed according to which the barrels made conical on their exterior surface were fastened in the similarly conically shaped integral chamber-piece by cold pressing. But this construction has not been successfully carried into practice. The reason for failure of this method is that the fastening of the barrels to the chamber-piece is too weak and is not adapted to resist for any length of time the pressure or force of the powder gases acting on the barrel in the direction of its axis. These inconveniences induced

the manufacturers of such guns to abandon the method and to adopt screwing the barrels with a short thread into the chamber-piece. But neither does this mode of connection answer the purpose, as it does not obviate the entering of powder gases into the thread and any corrosions of the latter resulting therefrom. For this reason also this mode of connection was condemned and replaced by another construction in which the chamber-piece was subdivided into two halves and each half made in one piece with

the barrel appertaining thereto. The two halves of the chamber-piece were then connected with each other by a dovetail-joint. Though this construction may comply with the mere technical requirements, it does not however, satisfy the economical requirements, as the said construction can only be performed with great difficulty and considerable costs.

The present invention consists in pressing the barrels into the bores of the chamber-piece, but obviates at the same time the drawbacks of the said known cone connection by putting onto and over the ends of the cylindrical barrels the likewise cylindrical bores of the chamber-piece or breech until the end faces of the barrels are flush with the end or rear face of chamber-piece, and then establishing between the barrels and the chamber-piece a special connection based upon and acting by clamping pressure and friction. This connection is effected by enlarging the external diameter of the extremities of the barrels by swaging or widening the same. The integral unitary breech or chamber-piece is furnished with bores the inner diameter of which is approximately the same as the external diameter of the barrels in such a manner that even after roughening the contacting surfaces the barrels may conveniently be passed into the bores of the chamber-piece and firmly and tightly connected therewith by swaging the barrel ends within the bores by means of a mandrel or the like.

In the accompanying sheet of drawings is shown by way of example a practical embodiment of the novel barrel connection of a double barreled gun; Fig. 1 being a cross sectional view and Fig. 2 an elevation of the said connection.

Similar letters of reference designate like parts throughout the figures.

According to the mode of carrying the invention into practice the breech *b* is provided with the usual locking hooks *a* and the inner diameter of the cylindrical bores of the unitary chamber-piece or breech *b* correspond to the external diameter of the rear ends of the barrels *c* in so far that the chamber-piece notwithstanding a suitable roughening given to the contacting faces, may be passed without jamming onto the barrels. After the chamber-piece has been placed or passed onto the barrels the ends of the latter embraced by the chamber-piece;

are widened or swaged in well known manner by means of a mandrel or other suitable device to such an extent that a reliable frictional connection is obtained between the barrels and the chamber-piece. The rear end of the barrels at the rear face of the chamber-piece may be flanged if desired or required. For taking up the flange the chamber-piece may be provided at its rear face with a suitable annular recess.

I claim:—

1. An improved method of connecting barrels of a multiple barreled gun to a unitary chamber-piece or breech, which comprises providing the breech with longitudinal bores of approximately the same diameter as that of the breech ends of the barrels, roughening the inner surface of the bores and the outer surface of the breech ends of the barrels, placing the barrels with the breech ends into the bores of the breech and then swaging the barrels in order to clamp them into the bores of the breech.

2. An improved method of connecting barrels of a multiple barreled gun to a unitary chamber-piece or breech, which comprises providing the breech with longitudinal bores of approximately the same diameter as that of the breech ends of the barrels, providing an annular recess in the rear face of the breech around each bore therein, roughening the inner surface of the bores and the outer surface of the breech ends of the barrels, placing the barrels with the breech ends into the bores of the breech, swaging the barrels in order to clamp them into the bores of the breech, and then flanging the extreme breech ends of the barrels so that the flanges fit into the respective annular recesses in the breech.

3. An improved method of connecting barrels of a multiple barreled gun to a unitary chamber-piece or breech, which comprises providing the breech with longitudinal bores of approximately the same diameter as that of the breech ends of the barrels, roughening the inner surface of the bores and the outer surface of the breech ends of the barrels, placing the barrels with the breech ends into the bores of the breech, and then pressing the breech ends of the

barrels from the inside outwardly against the bores so as to effect intimate secure frictional contact between the barrels and the breech.

4. An improved method of connecting barrels of a multiple barreled gun to a unitary chamber-piece or breech, which comprises providing the breech with longitudinal bores of approximately the same diameter as that of the breech ends of the barrels, providing an annular recess in the rear face of the breech around each, bores therein corresponding to the flange on the barrels, roughening the inner surface of the bores and the outer surface of the breech ends of the barrels, placing the barrels with the breech ends into the bores of the breech, pressing the breech ends of the barrels from the inside outwardly against the bores so as to affect intimate secure frictional contact between the barrels and the breech, and then flanging the extreme breech ends of the barrels into the respective annular recesses.

5. An improved breech connection for multiple barreled guns, comprising a plurality of barrels and a unitary integral breech provided with longitudinal bores the number of which corresponds to that of the barrels and having approximately the same diameter as the breech ends of the barrels, the latter ends on the external surface and the internal surface of the bores being roughened, and the breech ends of the barrels being placed in the bores and then swaged into place.

6. An improved breech connection for multiple barreled guns, comprising a plurality of barrels and a unitary integral breech provided with longitudinal bores the number of which corresponds to that of the barrels and having approximately the same diameter as the breech ends of the barrels, the latter ends on the external surface and the internal surface of the bores being roughened, an annular recess around each bore, a flange on the extreme rear end of each barrel, and the breech ends of the barrels being placed in the bores and swaged into place with the flanges fitting into the recesses.

CARL THILO MÜNZER.
